UNITED STATES PATENT OFFICE.

DAVID CARILE EGBERT, OF KENNEDY, MISSOURI.

GAUGE.

1,403,304.

Specification of Letters Patent. Patented Jan. 10, 1922.

Application filed March 5, 1920. Serial No. 363,386.

To all whom it may concern:

Be it known that I, DAVID C. EGBERT, a citizen of the United States, residing at Kennett, in the county of Dunklin and State 5 of Missouri, have invented new and useful Improvements in Gauges, of which the following is a specification.

This invention relates to gauges and has for its object the provision of a device adapted for use by carpenters in marking window jambs so as to indicate the exact points at 10 which holes should be bored for forming the pulley openings.

An important object is the provision of a 15 device of this character which is adjustable whereby it may be used for marking the holes to be bored for the accommodation of pulleys, regardless of whether wide or narrow sashes are to be used, the construction 20 being such that when the parts are adjusted and the device is subsequently given a slight blow with a hammer, the proper marks will be made upon the window jamb.

An additional object is the provision of a 25 device of this character which will be simple and inexpensive in manufacture, highly efficient in use, durable in service, and a general improvement in the art.

With the above and other objects and advantages in view, the invention consists in 30 the details of construction to be hereinafter more fully described and claimed, and illustrated in the accompanying drawings in which—

35 Figure 1 is a sectional view through a portion of a window jamb showing my device associated therewith and in contracted position,

Figure 2 is a side elevation,

40 Figure 3 is a cross sectional view showing the adjustable members moved outwardly to their maximum degree,

Figure 4 is a plan view,

45 Figure 5 is a perspective view of one of the movable members, and

Figure 6 is a detail plan view of the movable members removed.

Referring more particularly to the drawings, the letter A designates a window jamb 50 which it is desired to mark for the boring of the holes in forming the pulley openings. In carrying out my invention I provide a body 10 which may be formed as a casting and this body is rectangular in form and 55 provided centrally of its top with a projection 11 and longitudinally and centrally of

its bottom with a rib 12. This rib is adapted to be inserted within a transverse recess B in the jamb A. The body 10 has formed therein spaced parallel cylindrical holes 13 60 and is provided in its top with a pair of threaded holes 14 leading into the holes 13.

Associated with each side of the body 10 is a plate 15 which has its lower edge formed to provide a plurality of penetrating prongs 65 or tines 16 and it will be observed that these plates 15 are of the same length as the body 10 and of such height or width with respect thereto that the prongs or tines 16 will extend beyond the adjacent face of the body. 70 The plates 15 each carry cylindrical studs 17 and 18, the former being longer than the latter and the studs on one plate are arranged the reverse of those on the other plate, that is the long and short studs are 75 in alternation. These studs 17 and 18 extend into the holes 13 and are engaged by set screws 19 threaded into the holes 14.

In the use of the device, the body is so placed that the rib 12 thereon will be disposed within the groove B provided for the reception of the parting strip. The set screws 19 are loosened and the plates 15 are moved away from or toward the sides of the body a sufficient degree so that the distance 80 between the plates will be the distance between the centers of the pulleys, and this of course depends entirely upon the thickness of the sash. The device being thus positioned and the plates 15 being thus adjusted and the 85 set screws 19 tightened, the operator strikes a light blow with a hammer or other implement, upon the extension or projection 11 whereupon the penetrating prongs or tines 16 will be driven into the jamb and will indicate the centers of holes to be bored by a brace and bit in forming the pulley receiving slots. The device is then of course removed from the window jamb and it will be 90 found that each plate or rather the penetrating prongs thereon has left four indentations in the face of the jamb and when holes of proper diameter are bored with these points as their centers the pulley receiving slots will be formed. 95

From the foregoing description and a study of the drawings it will be apparent that I have thus provided a very simply constructed and easily set and operated device whereby the necessary markings for pulley 100 slots may be quickly, easily, and accurately made, the device thereby being a great labor 110

saver besides improving the quality of the work by making it accurate.

While I have shown and described the preferred embodiment of my invention, it is of course to be understood that I reserve the right to make such changes in the form, construction, and arrangement of parts as will not depart from the spirit of the invention or the scope of the subjoined claim.

10 Having thus described my invention, I claim:

A device of the character described comprising a rectangular body having formed upon its underside a longitudinally extending central rib adapted for engagement within the parting strip receiving groove of a window jamb, said body being provided

upon its upper side with an impact receiving projection, said body being further provided with spaced parallel holes extending 20 entirely therethrough from side to side, a plate disposed at each side of the body and having one edge formed with a plurality of spaced penetrating points, studs carried by said plates and slidably engaged within 25 said holes whereby the position of said plates may be varied with respect to their distance from the sides of the body, and screws threaded into the body and engaging said studs for holding said plates in adjusted 30 positions.

In testimony whereof I affix my signature.

DAVID CARILE EGBERT.
